UNITED STATES PATENT OFFICE.

CHARLES M. HATTENBERGER, OF KETTLE RIVER, MINNESOTA.

BATTERY-BOX.

1,190,405.

Specification of Letters Patent. Patented July 11, 1916.

Application filed July 27, 1915. Serial No. 42,199.

To all whom it may concern:

Be it known that I, CHARLES M. HATTENBERGER, a citizen of the United States, residing at Kettle River, in the county of Carlton and State of Minnesota, have invented certain new and useful Improvements in Battery-Boxes, of which the following is a specification.

My invention relates to a container for a battery of cells, and more particularly to a simple, cheap, and effective connecting means associated therewith.

The primary object of my invention is to provide a container for a battery of cells having an improved connecting circuit terminal carried by the cover of said container, whereby to automatically connect the cells contained therein.

With the above and other objects in view my invention resides preferably in the construction, combination, and arrangement of parts as hereinafter set forth in the specification and illustrated in the accompanying drawings, in which—

Figure 1 is a vertical sectional view taken through the longitudinal axis of the container. Fig. 2 is a longitudinal sectional view taken on the line 2—2 of Fig. 1 looking in the direction of the arrow. Fig. 3 is a transverse vertical sectional view of my invention. Fig. 4 is a fragmentary plan view of a portion of the container showing the circuit terminals associated therewith.

Similar reference characters indicate similar parts throughout the various views of the drawings.

In the drawings, wherein the preferred embodiment of my invention is illustrated, I provide a container 1 of any suitable material having an insulating and water proof lining 2 into which is receivable a plurality of cells forming an electric battery and designated 3.

The battery connecting means is carried by a cover 4 hinged at 5 and having a hasp lock at 6. The cover 4 is provided with a plurality of vertical openings 7 in which are disposed insulating bushings 8 which are adapted to receive the circuit terminals 9 of the cells 3. The connecting elements include a plurality of blocks 10 vertically slideable in said bushings 8 and having the terminals 11 of suitable electrical conductors 12 connected thereto. A supplemental cover 13 is provided and is designated 13, said sup-

plemental cover being hinged as at 14 and having a lock as at 15. The under surface of the cover 13 is recessed as indicated at 16 to receive a conductor carrying block 17 of insulating material and a protecting plate 18. The block 17 is grooved as indicated at 18 to receive the conductors 12. As shown to advantage in Fig. 2, the cells are connected in series, but it will be understood that any desired arrangement of conductors 12 may be had in order to vary the manner of connecting said cells. In order to maintain an even and positive contact between the blocks 10 and the binding posts 9 coil springs 20 are interposed between the blocks 17 and the blocks 10. Suitable retaining screws 21 pass through said plate 18 and the block 17 into the cover 4 for retention of said block and plate thereon. The terminals of the connecting means are designated 22 and are disposed through openings 23 provided in the plate 18. Needless to say, the conductors 12 are of flexible wire or the like so as to allow of ample movement of the blocks 10 to accommodate different sizes of binding posts.

It will be noted that the construction of this battery container permits the quick and sure connection of a plurality of cells, the same being as readily adapted for connecting storage batteries as the ordinary dry cell. Particular attention is directed to the peculiar construction of the cover 4, this construction practically entirely excluding all foreign substances, moisture and the like which are detrimental to the proper operation of electric batteries, and thereby enhances their efficiency. It will be noted that access may be had to the container without changing the connections of the connecting members, but if it is desired to change the connections from series to parallel, the supplemental cover 13 may be readily removed and access gained to the conductor carrying plate 17 and the protecting plate 18.

From the above description taken in connection with the accompanying drawings, it is thought that the construction, operation, and advantages of my invention may be readily had and it is desired that it be understood that, while I have shown and described the same as embodying a peculiar construction, I do not desire to be limited to said construction other than by the import of the claims appended.

2
What is claimed is:

1. A battery container, including a receptacle, a cover therefor having a plurality of recesses, circuit terminals in said recesses, battery terminals receivable in said recesses, conductors associated therewith, a supplemental cover, said circuit terminals being complementary to the battery terminals of the cells to automatically connect the same when the cover is closed.
2. A connector for a battery of cells, including a container, a cover therefor, said cover having a plurality of apertures, circuit terminals in said apertures, conductors associated therewith, battery terminals receivable in said apertures, a supplemental cover, and protecting means associated therewith, said circuit terminals being complementary to the binding posts of the cells

Copies of this patent may be obtained for five cents each, by addressing the "Commissioner of Patents, Washington, D. C."

to automatically connect the same when the 20 cover is closed.

3. A battery container, including a receptacle, a receptacle for reception of a battery of cells, a cover therefor, said cover having a plurality of apertures, yieldable circuit terminals in said apertures, battery terminals receivable in said apertures, conductors associated therewith, a supplemental cover, and insulating and protecting means associated with said first mentioned cover, as 30 and for the purpose set forth.

In testimony whereof I affix my signature in presence of two witnesses.

CHARLES M. HATTENBERGER.
